(57) CLAIM

The ornamental design for a shoe as shown and described.

DESCRIPTION

FIG. 1 is a front and right side perspective view of a shoe, showing my new design;

FIG. 2 is a right side view thereof;

FIG. 3 is a left side view thereof;

FIG. 4 is a front view thereof; and,

FIG. 5 is a top view thereof.

The bottom view is not shown and forms no part of the claimed design. The dash-dot lines indicate the boundaries of the claimed subject matter and themselves form no part of the claimed design. The features shown in dash-dash broken lines depict portions of the shoe that form no part of the claimed design.

1 Claim, 5 Drawing Sheets
